FIG. 11

FIG. 12

FIG. 1 is a perspective view of a xerographic processor housing, suitable for enclosing the operative elements of a xerographic printing unit, showing our new design; FIG. 2 is a front elevational view of the housing of FIG. 1;

FIG. 3 is a top plan view of the housing of FIG. 1;

FIG. 4 is a left-hand side elevational view of the housing of FIG. 1;

FIG. 5 is a right-hand side elevational view of the housing of FIG. 1;

FIG. 6 is a rear elevational view of the housing of FIG. 1;

FIG. 7 is a perspective view of another embodiment of our xerographic processor housing design, this embodiment suitable for enclosing the operative elements of a xerographic charging unit;

FIG. 8 is a front elevational view of the housing of FIG. 7;

FIG. 9 is a top plan view of the housing of FIG. 7;

FIG. 10 is a left-hand side elevational view of the housing of FIG. 7;

FIG. 11 is a right-hand side elevational view of the housing of FIG. 7; and

FIG. 12 is a rear elevational view of the housing of FIG. 7.

We claim:

The ornamental design for a xerographic processor housing, as shown and described.
